SUPPLY CONTROL FOR PAPER TOWEL DISPENSERS

Philip A. Wooster, San Rafael, Calif.

Application December 31, 1941, Serial No. 425,176

7 Claims. (Cl. 242—55.2)

This invention relates to controlling the paper supply in paper towel dispensers, and relates particularly to means designed to prevent the use of unauthorized paper in dispensers which are designed for paper towels of a particular manufacturer and quality.

It is customary for manufacturers and distributors of paper towels to provide dispensers for towels and also to supply rolls of toweling to be used in the dispensers. In order to discourage use of unauthorized toweling or toweling of an inferior grade, it has become common practice to provide dispensers with means to prevent any but a particular type of towel roll being inserted, and then provide toweling therefor in rolls which cannot readily be duplicated by other manufacturers.

Some of the dispensers now in use include means to support a roll of toweling at its ends only and means consisting of a stud or projection to prevent insertion of a roll of normal length, unless it is cut in a particular manner to enable it to pass over the stud or projection. A shorter roll may be inserted but will not be supported properly. In some cases, however, a roll which is considerably shorter than the length properly used in the dispensers, will drop to the bottom of the dispenser and function very much in the manner intended for a properly supported roll.

It is the object of the present invention to provide a simple and inexpensive means for insuring against the use of unauthorized paper in a towel dispenser and especially to insure against the use of short rolls in a dispenser which has control means depending for successful functioning on the towel roll being of a predetermined length.

Other objects and advantages of the invention are made apparent in the following specification wherein the same is described in detail and wherein reference is made to the accompanying drawing illustrating one form of the invention.

In the drawing:

Fig. 1 is a sectional view through a towel dispenser embodying the present invention;

Fig. 2 is a sectional view taken on line II—II of Fig. 1;

Fig. 3 is a perspective view of a roll of paper toweling of the kind illustrated in Figs. 1 and 2;

Fig. 4 is a perspective view of a portion of the bottom wall of the dispenser illustrated in Figs. 1 and 2;

Fig. 5 is a perspective view of one of the towel supporting members illustrated in Fig. 1 and

Fig. 6 is a perspective view of a modified form of the supporting member illustrated in Fig. 5.

The towel dispenser shown in Figs. 1 and 2 of the drawing is illustrated as having a bottom 10 and a pair of end walls 11 enclosed within a suitable cover 12. Within the dispenser is a measuring or towel advancing roller 13 over which paper from a roll of toweling 14 is trained. The roller 13 is connected with a crank or other suitable device for causing it to rotate so that the paper trained over it will be advanced and fed from the roll 14 to a position without the cabinet where it may be grasped and torn off in lengths suitable for use. The roller 13 may be also, if desired, equipped with any conventional stop mechanism or time delay mechanism for measuring the lengths of toweling advanced by it for affecting a delay between successive dispensing operations. As these operating mechanisms form no part of the present invention and have no bearing on the same, they are not illustrated herein. On the opposed faces of the end walls 11 are secured a pair of supports 15. These supports incline forwardly and toward the roller 13 so that the supply roll 14 the ends of which rest upon the supports 15 will gravitate toward and come to rest against the roller 13. Each of the supports 15 presents a relatively narrow supporting surface so that the supply roll 14 must be of a predetermined minimum length in order properly to be supported by them in its intended position.

On one of the side walls 11 a stud 16 projects inwardly a distance substantially equal to the width of the supporting surface of the support 15. The paper of the supply roll 14 is wound upon a core 17 usually a pasteboard tube and is provided as illustrated in Fig. 3 with a groove 18 extending transversely of the end which corresponds with the end wall 11 of the dispenser which carries the stud 16.

The supply roll 14 is of a length just to fit between the end walls 11 and the groove 18 is of a depth to pass over the stud 16 upon insertion of the supply roll. One advantage of the structure thus far defined, is that a supply roll of normal length cannot be introduced into the dispenser unless it is provided with the groove 18. While a supply roll sufficiently shorter than standard length may be placed in the dispenser, it will not rest upon the supports 15. Transversely extending members 19 and 20 which reinforce the side walls 11 are preferably positioned to prevent insertion of a supply roll except by the normal path in which the stud 16 is posi-

tioned. Other advantages of this structure and method of controlling the paper supply in towel dispensers are set forth in Patent No. 2,232,968 for "Towel dispenser and supply roll therefor," issued to Lawrence L. Price and Maurice E. Maltby on February 25, 1941.

It has been found, however, that if the unauthorized or inferior grade of paper attempted to be inserted in the dispenser is considerably shorter than a standard roll, it will pass between the innermost edges of the supports 15 and rest entirely upon the bottom 10 of the dispenser where it will in some cases function as efficiently or nearly as efficiently as though it were properly supported upon the supports 15.

The present invention insures against successful operation of the short supply roll through the structure now to be described.

As shown in Figs. 1, 2 and 4, the bottom wall 10 of the dispenser is provided with a plurality of upwardly directed spikes or points 21. These points 21 may be constructed in any suitable manner, but are inexpensively provided by punching out triangular sections of the bottom wall along 2 sides of their triangular shape, and bending them upwardly as shown in Fig. 4. This method of construction has the advantage of providing holes in the bottom wall of the dispenser, which serve the purpose of permitting dust and small bits of paper which fall from the supply roll to escape, rather than to accumulate within the dispenser where they may tend to foul or soil the toweling just before it is dispensed. The upwardly directed points of the members 21, provide a surface which will not support a roll of paper toweling without injury thereto, and which will destroy the toweling by tearing it if the roll is rotated as it must be during a normal dispensing operation. Consequently, any roll of toweling placed within the dispenser which is sufficiently short to avoid both of the supports 15, will rest upon the serrated surface presented by the points 21 and will be destroyed if an attempt is made to dispense it.

A further means for preventing the use of short rolls and one which may be used either instead of or in addition to the points 21 on the bottom wall is illustrated in Fig. 5. In this figure one of the supports 15 which is conventionally of simple angular shape is shown as having an inwardly projecting flange 23, wider than its supporting surface and have an upwardly turned serrated edge 24 upon which the paper roll will rest if it is too short to be supported in normal position on the supports 15. A modification of the structure shown in Fig. 5 is illustrated in Fig. 6 wherein a serrated edge 25 is shown as extending inwardly in place of the upwardly extending serrated edge 24. In either of the cases illustrated in Figs. 5 and 6 the supply roll which is too short and therefore falls between the normal supporting surface will become entangled with, damaged by, or lodged against rotational movement by the serrated portions of the supporting member which in normal operation of the dispenser with a towel roll of proper length will have no effect whatsoever, on the toweling being dispensed.

Either the structure shown in Fig. 4 or those shown in Figs. 5 and 6, or both, may be included with the conventional dispenser at extremely low cost to provide an effective and efficient guard against the use of paper other than that intended to be used in the dispenser.

The particular shapes of the points and serrations herein illustrated, as well as their size, and arrangement is a matter of choice. Other modifications in the structures herein disclosed may be resorted to without departing from the scope of the appended claims by which the invention is defined.

Having thus described my invention, what I claim and desire to secure by Letters Patent is:

10. The combination with a towel dispenser having means for supporting a roll of toweling at its ends, and control means to prevent any but an authorized roll of toweling being so supported therein, means within the dispenser to lacerate the toweling if it is not properly supported therein.
15. In a towel dispenser having supports to hold a roll of toweling spaced from the bottom of the dispenser and means to prevent insertion in the dispenser of an unauthorized roll unless it is too short to rest on said supports, a serrated surface on the bottom of the dispenser to injure the toweling if it is not properly supported therein.
20. In a towel dispenser having narrow supports for opposite ends of a roll of toweling and means to prevent insertion in the dispenser of an unauthorized roll unless it is too short to rest on said supports, metal points arranged below and between said supports whereby any roll of toweling too short for proper engagement with the supports will, if inserted in the dispenser be torn upon an attempted dispensing operation.
25. In a towel dispenser having supports for the ends only of a roll of toweling to be dispensed so that a roll too short for the supports will rest upon the bottom of the dispenser and means to prevent insertion in the dispenser of an unauthorized roll unless it is too short to rest on said supports, a plurality of points formed on the bottom of the dispenser by punching and bending up pointed portions of the metal of which the bottom is formed whereby the roll resting on the bottom will be lacerated.
30. In a towel dispenser having supports for the ends only of a roll of toweling and means to prevent insertion in the dispenser of an unauthorized roll unless it is too short to rest on said supports, metal points arranged below and between said supports whereby any roll of toweling too short for proper engagement with the supports will, if inserted in the dispenser be torn upon an attempted dispensing operation.
35. In a towel dispenser having supports for the ends only of a roll of toweling and means to prevent insertion in the dispenser of an unauthorized roll unless it is too short to rest on said supports, serrated metal edges arranged adjacent said supports to engage and tear the toweling if it is not properly supported by them.
40. In a combination with a towel dispenser having spaced supports for a roll of toweling to be dispensed and having a stud arranged to project into the path of a roll of toweling being inserted toward said supports whereby any roll or toweling sufficiently long to rest properly on said supports must be grooved at its end to pass over said stud, means to prevent the use of short rolls of toweling comprising towel lacerating members positioned below the supports to engage the roll if it falls below the supports.
45. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.
50. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.
55. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.
60. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.
65. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.
70. In combination with a towel dispenser having spaced supports for a roll of toweling to be dispensed and having a stud arranged to project into the path of a roll of toweling being inserted toward said supports whereby any roll of toweling sufficiently long to rest properly on said supports must be grooved at its end to pass over said stud, means to prevent the use of short rolls of toweling comprising a plurality of points cut and bent upwardly from the bottom of the dispenser to engage and tear the toweling if the roll falls below the supports.

PHILIP A. WOOSTER.
